UNITED STATES PATENT OFFICE.

JOSEPH H. LEHMAN, OF HASBROUCK HEIGHTS, NEW JERSEY.

CIRCUIT CONTROLLER FOR IGNITION SYSTEMS.

1,415,370.

Specification of Letters Patent.

Patented May 9, 1922.

Application filed February 26, 1918. Serial No. 219,229.

To all whom it may concern:

Be it known that I, JOSEPH H. LEHMAN, a citizen of the United States, and resident of Hasbrouck Heights, in the county of Bergen and State of New Jersey, have invented certain new and useful Improvements in Circuit Controllers for Ignition Systems, of which the following is a specification.

This invention is primarily adapted for 10 use in a combined timer and distributor for effecting the make-and-break of the primary or battery circuit and the distribution of the induced secondary or high-tension current to the spark plugs or other igniters of an internal combustion engine, although certain features may be used separately in timers, distributors, or other circuit controlling devices.

In my prior Patent No. 1,251,249, issued 20 December 25, 1917, I have illustrated and broadly claimed a construction in which the polarity of the make-and-break contacts of the primary circuit is reversed during each rotation so as to avoid pitting the contact faces, to effect the complete discharge or collapse of the coil, and to secure other advantageous results. My present invention in certain of its embodiments involves means for effecting said intermittent polarity reversing by a simpler, cheaper and equally if 30 not more effective mechanism.

The body or casing has connected to it the terminals of conductors leading to the battery and the several spark plugs and it is 35 usual to advance or retard the spark by a rotary movement of the body or casing. This results in a continual tendency of the conductors to become loosened or disconnected at said terminals. By means of my invention such relative movement of the casing and conductors is rendered unnecessary and is avoided, and the objection referred to above, in regard to loosening, is obviated. In certain embodiments of my present invention, I am able to secure this result even 45 though the polarity reversing feature be omitted.

A further important feature of my invention results in such a designing and arrangement of the parts that they may be very easily and quickly separated for repair, replacement or cleaning. The interrupter or make-and-break device may be disconnected upon the removal of a single fastening member and replaced by other designs. A substitution of interrupter may change the de-

vice from a normally open circuit one to a normally closed circuit one, or vice versa.

A further important feature of my invention enables me to use stamped or pressed 60 sheet material such as sheet metal for the cover or casing portion to which the secondary circuits are connected. This facilitates standardization and greatly increases the durability and permits the quick and 65 easy interchange of the small inexpensive insulation members in case they become defective or broken.

Many other important features of my invention will be referred to hereinafter in 70 connection with a detailed description of certain specific embodiments thereof. In certain respects, my present invention is an improvement on that shown in my prior application Serial No. 199,242, and it may be 75 used in connection with certain features of the invention shown in my Patent No. 1,311,902, issued August 5, 1919.

In the accompanying drawings, to which reference is to be had, I have illustrated certain 80 embodiments of my invention, but it will of course be understood that these are to be considered in an illustrative rather than in a limiting sense, and that various changes, rearrangements and substitutions 85 may be effected within the scope of the appended claims without departing from the spirit of my invention. In these drawings,

Figure 1 is a central longitudinal section 90 through a complete device;

Figure 2 is a transverse section on the lines 2-2 of Figure 1;

Figure 3 is a plan view of the interrupter housing or collar;

Figure 4 is a top plan view of the main 95 body or casing;

Figure 5 is a central, longitudinal section through the body with the interrupter housing or collar in position, the view being taken substantially on the line 5-5 of Figure 4 and at right angles to the plane of Figure 1;

Figure 6 is a side elevation of the current interrupter or make-and-break device;

Figure 7 is a perspective view of the locking key and operating handle for the interrupter housing;

Figure 8 is a plan view of a normally closed circuit interrupter which may be substituted for the normal open circuit interrupter shown in Figure 2; and

Figures 9 and 10 are side elevations show-

ing forms in which constant polarity current may be delivered to the contacts of the interrupter.

In the main illustrated embodiment of my invention, I provide a body or casing member 10 and a cover member 11, both preferably formed of metal and adapted to carry and protect the various moving parts. The casing or body 10 may be formed of cast iron and includes a depending sleeve 12 constituting a bearing for the main shaft 13. This sleeve may extend through and be carried by a clamping collar 14 and the latter may have a split portion with outwardly extending, spaced wings 15 which may be drawn together by a clamping bolt to rigidly hold the body in position. The clamping collar or support 14 may be secured to the engine frame or to any other suitable member in any desired manner, but preferably so as to leave a pinion 16 on the lower end of the shaft 13 exposed for engagement with a gear on the cam shaft or other driven part of the engine. Obviously, the means for transmitting power to the shaft 13 to insure the proper speed of rotation of the latter forms no portion of my present invention.

At the upper end of the sleeve 12, the body has a dished or cup portion 17 serving to receive the rotating part of the interrupter. The upper edge of this cup constitutes a flange 18, for supporting the interrupter housing or collar, while the peripheral wall of the cup has the terminals and brushes for conducting the current to and from the interrupter. Outside of this flange 18 is a second upstanding collar or flange 19, substantially concentric therewith and to which is secured the cover 11 which forms the upper half of the casing.

The shaft 13 projects upwardly through the cup portion 17 coaxial therewith and the portion 20 of the shaft above the lower or bottom wall of the cup portion is preferably of reduced diameter. Rigidly clamped on this reduced portion 20 is a head or disc 21 of insulation material which carries the relatively movable contacts of the interrupter. The head 21 may seat on a collar or washer 22 which latter may seat on a shoulder at the lower end of the reduced portion 20 of the shaft, and these parts may be rigidly secured together by a nut 23 threaded on the shaft as indicated particularly in Figure 1. To prevent rotation of the head 21 on the shaft, the reduced portion of the latter may be flattened at one side, as indicated in Figure 2, or may be keyed in any other suitable manner.

The head or disc 21 has embedded therein or secured thereto two semi-circular collector ring sections 24 and 25 insulated from each other. These are shown as being in the same transverse plane on the periphery and having their peripheral surfaces in arcs of the

same circle. The two collector ring sections 24 and 25 have posts 26 and 27 extending up through the upper surface of the head and serving to support the two relatively movable contacts 28 and 29 of the interrupter or make-and-break device. As shown, the post 26 extends up from the collector ring 24 and carries a contact member 28 which may be adjusted slightly in position by means of its supporting screw. The contact member 29 is carried by a spring metal leaf 30 secured to the post 27 which extends up from the collector ring 25.

Mounted on an upwardly extending pivot 32 is a bell-crank lever 33 normally retained in the position indicated in Figure 2 by a spring 34 and a pair of stops 35 and 36. The outer end of this bell-crank lever, when operated by engagement with the interrupter housing or collar, as hereinafter described, moves about its pivot and effects a corresponding movement of a hook spring 37 secured to and carried by the contact carrying spring 30. Thus, the contacts 28 and 29 are permitted to come together and separate to make and break the current during rotation of the head or disc 21 and the parts carried thereby. The bell-crank lever itself may be of insulation material so that its contact with the spring 37 does not result in any loss or short-circuiting of the current, or the lever, if made of metal, may have an insulation face 38.

The parts of the interrupter as above described embody certain advantages so far as simplicity, reliability and durability are concerned, but so far as certain other aspects of my invention are concerned they may be replaced by the construction shown in Figure 2 of my prior application Serial No. 199,242, or Figures 7 or 9 of my Patent 1,311,902, or other forms may be used.

The interrupter housing or collar in its preferred form is shown separately in Figure 3. This includes a split ring 40 of slightly reduced diameter adjacent to its upper edge so that it may be contracted, lowered into position within the flange 18 and then permitted to expand and fit beneath a shoulder 41 on the flange 18 as shown particularly in Figures 1 and 5. In this position, the collar is free to oscillate but cannot move axially. The inner surface of the collar or housing presents a plurality of projections or surface irregularities 42 equally spaced and corresponding in number to the desired number of current interruptions per revolution of the rotary member including the shaft 13 and the parts carried thereby.

In the specific form illustrated, the device is adapted for use in a four-cylinder engine and there are therefore four of these projections. They are of such form, shape and position that as the interrupter head 21 ro-

tates, the outer tip end of the bell-crank lever 33 comes into contact with these projections in succession and effects successive relative movements of the contacts 28 and 29. The projections intercept the path of the lever 33 to only a slight extent so that the relative movement of the contacts is small and the end of the lever may slip past each projection after being moved about its pivot to a limited extent by such engagement.

The timing of the spark may be advanced or retarded by an oscillation of this interrupter housing. Although this oscillation is preferably in respect to the main casing member, the latter being stationary, the same oscillation may be secured by turning the two together if they be rigidly connected. For effecting such oscillation, a portion of the flange 18 is shown as cut away and a slot is formed through the wall of the body or casing 10. As illustrated, this slot 43 is through the bottom wall of the casing closely adjacent to the flange 18 or registering with the break in the latter. An operating member 44 projects up through this slot and has a transversely extending portion 45 which may be rigidly secured to the outer surface of the interrupter housing. As shown, this transverse portion is adapted to be secured by a pair of screws entering the interrupter housing at opposite sides of the gap in the latter so that when the operating member is secured to the housing, the latter is locked in expanded form and permanently in position. To better insure against contraction of the split ring forming the interrupter housing, a portion 46 of the operating member may be punched out, as indicated in Figures 5 and 7, to enter between the ends of the housing. This may, in some constructions, permit of the elimination of the locking screws or, in any event, hold the parts together even though the screws should loosen or fall out. The lower end of the operating member 44, which projects to the exterior of the casing, as indicated in Figure 5, may be connected to an operating rod in a variety of different ways. As shown, the lower portion is offset to space it away from the peripheral wall of the cup portion 17, although this is not of particular consequence.

The length of the break in the flange 18 and the length of the attaching portion 45 of the operating member may be so proportioned in respect to each other that the ends of the attaching portion, when engaging with the ends of the flange 18, which seats the interrupter housing, may constitute stops for limiting the oscillatory movement of the housing. On the other hand, the length of the slot 43 may constitute the limiting means.

For delivering current to the collector ring

sections 24 and 25 of the interrupter, I provide a pair of brushes 50 and 51 at diametrically opposite points. If the collector ring sections be on the periphery of the head as illustrated, the brushes are in radial position but if the ring sections be on the under surface of the head as in my prior Patent No. 1,251,249, the brushes would face upwardly as there shown. These brushes may be of any suitable character similar to those used in connection with commutators and are resiliently pressed toward and into engagement with the ring sections 24 and 25 by suitable springs 52. Each brush is illustrated as being guided in a metal or other conducting sleeve 53 and each sleeve is carried in and supported by a sleeve or tube 54 of insulation material.

The peripheral wall of the cup portion 10 of the casing has diametrically opposed apertures 55 in which these brush supports are inserted and outside of each aperture and depending from the wall of the casing between the flanges 18 and 19 are split clamping collars 56, one of which is shown particularly in Figure 5 in dotted lines. By drawing together the flanged ends of the collar sections by a clamping bolt or screw, the brushes and their supports may be rigidly clamped in position. They may be very quickly and easily removed for cleaning, repair or replacement of the parts.

The conductors from the battery terminals may be electrically connected to the brushes 50 and 51 in any suitable manner. As shown, there are screws 57, beneath the heads of which the wires may be clamped, which have their inner ends extending into and electrically connected to the metal guiding sleeves 53 for the brushes.

As the rotation of the interrupter head brings first one collector ring section and then the other into engagement with each brush, and as the polarity of the brushes remains constant, it will be noted that the polarity of the collector rings is reversed twice during each complete rotation of the interrupter head. As the polarity of the collector rings is always the same as that of the corresponding contacts 28 and 29, it will be apparent that the polarity of these contacts is also reversed during each complete revolution. Thus, as the direction of current flow between the contacts is reversed at regular intervals, I avoid any pitting of the contact faces such as results from a continuous flow in one direction.

Contrary to the usual practice, it is possible, with my improved construction, to form the upper casing section or cover of inexpensive but rigid stamped sheet material. As the contacts are insulated from it, it may be of sheet metal. The cover 11 serves to support the terminals of the secondary circuit which correspond in number and general

position to the usually accepted practice. Each secondary terminal is in the form of a rod 60 constituting a metal conductor and is provided at its inner end with a head 61 with which a distributor brush 62 may cooperate. The rod 60 has an insulation block 63 thereon above the head 61 and extending through an aperture in the cover. This block presents a shoulder for engagement 10 with the inner surface of the cover.

A second insulation block 64 telescopes with the upper end of the block 63 and engages with the outer surface of the cover. By tightening a nut 65 on the conductor rod, 15 the parts are rigidly secured together and the rod is held properly insulated from the cover. This construction permits the use of inexpensive insulation blocks, as, for instance, pieces of porcelain and permits of the 20 quick and easy replacement of any block in case it becomes broken or defective.

To properly insure the accurate centering of the terminals and to avoid the necessity of having the insulation block 63 accurately 25 fitting the corresponding hole in the cover, the latter is preferably provided with a series of annular beads or ridges 66 concentric with the several holes and presenting inclined surfaces with which one of the 30 blocks may register. As shown, these beads extend upwardly and form a seat for the block 64 so as to accurately center the latter. This is a desirable but not an essential 35 feature and the bead may be omitted or may extend inwardly for engagement with the block 63 instead of outwardly.

The upper end of the shaft 13 carries a distributor head 67 which is of insulation material and may be of any construction 40 common in the art. As shown, the brush member 62 is secured to the upper side thereof and has its extremity in position to engage with or pass in operative position in respect to the heads 61 on the conductor bars 45 60. The brush has a spring 68 which constantly engages with the central contact 61 so that as the head rotates this is connected to the contacts of the annular series in succession.

50 As the casing sections 10 and 11 are both formed of metal, they are not only durable but may be constructed with great accuracy and be freely interchangeable. Various means may be employed for connecting the 55 two sections together. Merely for illustration, I have shown the flange 19 provided with a plurality of bayonet ridges 70 and have shown the lower edge of the casing section or cover 11 provided with corresponding 60 bayonet grooves 71 whereby the parts may be separated or secured together by a partial rotation of the cover in respect to the body of the casing.

To hold the parts against accidental un- 65 locking and to insure the proper final rela-

tive positioning of the parts in respect to the axis, I preferably employ some form of spring catch or stop. As shown particularly in Figures 2, 4 and 5, a button or knob 72 is carried by a spring 73 secured to the 70 inner surface of the flange 19 and projects through an aperture in one of the bayonet ridges 70. This may enter a slot or depression in the corresponding bayonet groove 71 of the casing and insure proper retention of 75 the parts.

One very material advantage of my improved construction above described is the ease with which all of the parts may be removed or rendered accessible for cleaning, 80 replacement, or repair. The brushes may be taken out by unclamping the collars 56 without disturbing any of the other parts, the distributor head 67 may be readily slipped off of the upper end of the shaft, and the 85 entire interrupter head and its parts may be removed from the shaft 13 merely by the removal of the nut 23 and without disturbing any of the other parts other than of course removing the cover 11 and the distributor head. The secondary terminals carried by the cover are easily and quickly removed at will.

The only part of the device which requires lubrication is the bearing of the shaft 13 95 and this may be readily oiled merely by removing the cover 11 as I have provided an oil passage 75 extending diagonally downward from the space between the flanges 18 and 19 to the side of the shaft below the 100 distributor head. It will be noted that there are no moving parts within the annular space between the two flanges and that therefore if an excessive amount of oil be deposited in the vicinity of the upper end of 105 the oil passage, it will not come into contact with any of the other moving parts. At most, it will merely flow around the annular passage and leave the device through the slot 43.

As to most of the important features of my invention, I may secure their full advantage without the utilization of the polarity reversing feature, if desired. As the interrupter head 21 may be easily removed, 115 it may be replaced by a head similar to that shown in Figure 9. This head has a body portion 21^a of insulation material and a single complete collector ring 24^a. This carries the post 27^a. The other contact carrying post 26^a is electrically connected to the shaft by a base strip held in position by the nut 23. Only a single brush 51^a is employed, this being connected to one terminal of the battery while the other terminal is 125 grounded; in other words, connected directly or indirectly to the shaft 13. This interrupter head may be readily inserted in place of that shown in Figures 1, 2 and 6 and without necessitating any change in the con- 130

struction except the plugging or omission of one of the brush apertures.

In case it is not desired to utilize the polarity reversing feature and at the same time 5 it is not desired to ground the current, I may employ the construction shown in Figure 10. Here, there are two separate, complete collector rings 24^b and 25^b, one connected to the contact post 26^b and the other to the contact 10 post 27^b by conductors through the body of the insulation head 21^b. The two separate brushes 50^b and 51^b engage with the two separate collector rings and are connected to the opposite terminals of the battery. This 15 head may be readily substituted for that shown in Figure 1 and merely necessitates the required change in the shape of the brush supports to bring one at a higher elevation than the other. These brushes may of 20 course be opposite to each other, rather than superposed, as somewhat diagrammatically shown in Figure 10.

Various other forms of interrupter heads 25 may be substituted as, for instance, I may put in one having normally closed contacts rather than normally open ones as shown in Figure 2. I have illustrated such a normally closed contact device in Figure 8.

In this construction, the head 21^c has a 30 bell-crank lever 33^c, one end of which has directly secured thereto a contact 29^c for movement into and out of engagement with the normally stationary or adjustable contact 28^c. A peripheral spring 34^c has one 35 end secured to the lever and normally tends to swing the latter in such a direction as to normally hold the two contacts in engagement with each other. As the outer end of the bell-crank lever engages with the projections in the interrupter housing, the contact 40 is first broken and then made. This device, per se, forms no portion of my invention but is illustrated merely as an interrupter head which may be inserted in my 45 improved construction in place of the other forms theretofore described in case it is desired to control a normally closed circuit system.

Having thus described my invention, what 50 I claim as new and desire to secure by Letters Patent is:

1. A timer having a substantially cup-shaped casing member, a shaft projecting through the end wall thereof, an interrupter 55 head within said casing and secured to said shaft, make-and-break contacts carried by said head, brushes carried by the peripheral wall of said casing and engaging with said head, and means in said head for connecting each brush to a separate make-and-break contact.

2. A timer having a substantially cup-shaped casing provided with a depending sleeve, a shaft journalled in said sleeve, a 65 pair of interrupter contacts carried by said

shaft within said casing, a pair of collector ring sections carried by said shaft within said casing, separate connections between each ring section and the corresponding contact member, and a pair of brushes carried 70 by the wall of the casing and engaging with said ring sections.

3. A timer having a substantially cup-shaped casing provided with a depending sleeve, a shaft journalled in said sleeve, an 75 insulation head carried by said shaft within said casing, a pair of semi-circular collector sections carried by said head, a pair of make-and-break contacts carried by said head, a separate connection between each 80 contact member and its corresponding section, a pair of brushes carried by the wall of said casing and engaging with said collector sections, and means within said casing for effecting a relative movement of said 85 contacts during the rotation of the latter with said head.

4. A timer having a rotatable member including a body portion of insulation material, a pair of spaced contact faces on the 90 periphery thereof, a pair of interrupter contacts carried by said body portion, connections between said contacts and said faces, and a pair of brushes each engaging with said contact faces in succession during the 95 rotation of said member.

5. A timer having a rotatable member including a body portion of insulation material, a pair of spaced contact faces on the periphery thereof, a pair of interrupter 100 contacts carried by said body portion, connections between said contacts and said faces, and a pair of brushes engaging with said contact faces during the rotation of said member.

6. A timer including a substantially cup-shaped casing, a rotatable member therein, having a pair of interrupter contacts and a pair of peripheral contact faces, a pair of brushes carried by the peripheral wall of 110 said casing for engagement with said faces, and an interrupter housing also carried by said peripheral wall for effecting a relative movement of said contacts during the rotation of said member.

7. A timer including a substantially cup-shaped casing, a rotatable member therein having a pair of interrupter contacts and a pair of peripheral contact faces, a pair of brushes carried by the peripheral wall 120 of said casing for engagement with said faces, and an interrupter housing also carried by said peripheral wall for effecting a relative movement of said contacts during the rotation of said member, said housing 125 having a limited oscillatory movement in respect to said casing.

8. A timer including a casing presenting an annular wall, an extensible and contractible interrupter collar seated within and 130

- free to oscillate in respect to said annular wall, and a rotatable member concentric with said wall and having a pair of interrupter contacts, and means engaging with 5 said collar to effect a relative movement of said contacts during the rotation of said member.
9. A timer including a substantially cup-shaped casing having an annular seat in the 10 inner surface of its peripheral wall, an interrupter housing expanded into said seat and free to oscillate, a rotatable member within said casing and having interrupter contacts, and means for engaging with said 15 housing and effecting their relative movement during the rotation of said member.
10. A timer including a casing member having an annular wall presenting a seat on the inner surface thereof, a split annular 20 collar extended into said seat, a member for oscillating said collar and normally preventing the contraction of the latter, a pair of interrupter contacts, and a member movable along said collar for effecting relative 25 movement of said contacts.
11. A timer including an annular wall provided with an annular seat upon the inner surface thereof, an annular split interrupter housing supported in said seat, a 30 handle member secured to said housing and having a portion between the spaced ends of the latter for normally preventing the contraction of the housing and serving to oscillate the latter, a pair of interrupter contacts, and a member rotatable within said 35 housing for engagement with the latter at successive spaced points for effecting relative movement of said contacts.
12. A combined timer and distributor including two metal casing sections, a rotatable 40 head within said casing, interrupter contacts carried by said head, a pair of brushes carried by one casing section and insulated therefrom and engaging with said head for 45 delivering primary current to said head, a plurality of secondary contacts carried by the other casing section and insulated therefrom, and a secondary current distributor rotatable with said head.
13. A device of the class described, including a cast metal casing member having two 50 annular concentric flanges, a cover member having bayonet joint connections with the outer flange, an interrupter housing 55 seated in and free to oscillate in respect to the other flange, an interrupter head concentric with said flanges and having make and break contacts, a shaft carrying said head and journaled in said casing, and an 60 oil passage leading from between said flanges to the bearing of said shaft.
14. A casing for timers including a cup-shaped body portion having an outwardly extending wall, a pair of upwardly extend- 65 ing concentric annular flanges, one of said flanges having means for the attachment of a cover thereto and the other serving as a seat for an interrupter housing, and a shaft bearing concentric with said flanges.
15. A head for timers including an insulation body, a pair of semi-circular collector rings insulated from each other, a pair of posts connected to said rings and extending to one end surface of said head, separate contacts connected to said posts, and 75 means for effecting a relative movement of said contacts during a rotation of said head.
16. A combined timer and distributor, including a cast metal casing member, a sheet metal cover member having bayonet joint 80 connections with said cast metal casing member, a shaft rotatably mounted in said cast metal casing member, a head carried thereby, make-and-break contacts carried by said head, means for delivering current to said 85 make-and-break contacts, including a primary circuit brush carried by said cast metal casing member and engaging with said head, distributor contacts carried by said sheet metal cover member, and a distributor brush rotatable with said head.
17. A timer including a rotatable member formed of insulation material, a pair of semi-cylindrical collector ring sections on the periphery thereof, a pair of posts connected to said sections and extending to one 90 end surface of said member, a make-and-break contact secured to one of said posts, a bell crank lever pivoted to said member and having a second make-and-break contact for cooperation with the first mentioned contact, said lever being electrically connected to the other post, a casing supporting 95 said member and having an annular series of projections in the path of movement of one end of said lever for swinging said lever and effecting the separation and engagement 100 of said make and break contacts a plurality of times during each rotation of said member, and a pair of brushes carried by said 105 casing and engaging with said collector ring sections for supplying current to said make-and break contacts and reversing the direction of flow of current through said contacts a plurality of times during each rotation of said member.
18. A timer having a head formed of insulation material, a shaft for supporting and rotating the same, a casing having a cup shaped body portion receiving said head and 110 having a bearing sleeve within which said shaft is mounted, said casing having an outwardly extending annular flange substantially in the plane of the upper surface of said head, make-and-break contacts carried 115 by the upper surface of said head, an annular member within said casing and having a plurality of spaced projections adjacent to

the inner edge of said flange, means carried by said head for engaging with said projections in succession during the rotation of the head to move one make-and-break contact in respect to the other, and a cover member secured to said casing at the outer edge of said flange.

19. A timer including a head formed of insulation material, a pair of substantially semi-cylindrical collector ring sections upon the periphery thereof and insulated from each other, a cup shaped casing receiving said head and of a depth substantially equal to the depth of said head, make-and-break contacts carried upon the outer surface of said head and separately connected to said collector ring sections, a lever pivoted on the outer surface of said head and an annular member carried by said casing above the plane of the upper surface of said head and having a plurality of projections with which one end of said lever may engage to effect a movement of one of said make-and-break

contacts in respect to the other during a rotation of said head. 25

20. A timer having a head formed of insulation material, a shaft for rotatably supporting the same, a cup shaped casing receiving said head and of a depth substantially equal to the thickness of said head 30 and provided with a bearing sleeve portion supporting said shaft, a pair of make-and-break contacts carried by said head a bell crank lever carried by said head, and an annular member carried by said casing above 35 said head and having a plurality of projections formed integral therewith and with which one end of said bell crank lever may engage in succession during the rotation of the head to move one of said make-and-break contacts in respect to the other. 40

Signed at New York, in the county of New York, and State of New York, this 23rd day of February, A. D. 1918.

JOSEPH H. LEHMAN.
